UNITED STATES PATENT OFFICE.

CHARLES A. MAY, OF TRENTON, NEW JERSEY, ASSIGNOR TO THE MADDOCK POTTERY COMPANY, OF SAME PLACE.

DESIGN FOR A COVERED DISH.

SPECIFICATION forming part of Design No. 24,996, dated December 24, 1895.

Application filed August 5, 1895. Serial No. 558,331. Term of patent 7 years.

To all whom it may concern:

Be it known that I, CHARLES A. MAY, a citizen of the United States, residing at Trenton, in the county of Mercer and State of New Jersey, have invented and produced a new and original Design for Dishes, of which the following is a specification, reference being had to the accompanying drawings, showing the same.

In the accompanying drawings, which form part of this specification, Figure 1 represents a top plan view of a covered dish embodying my design, and Fig. 2 a side view of the same.

The following are the leading features of the design: The dish A and cover B are semi-elliptical in form—that is to say, the sides and ends are arcs to two circles of different radii with a depression between the approaching lines at each end, producing the effect of a contraction at said points at the upper edge of the body of the dish—and on the ends of the dish are handles C C, which comprise side bars curved upward and inward and a transverse bar connecting the side bars. On the body of the dish are raised panels a in the center of its sides, panels b c on each side of the center, panel and end panels d, and between the several panels are the concavities or depressions, those at the ends of the side panels a producing the effect of contractions between the terminating lines of the

arcs of the two circles, and on the cover of the dish are corresponding panels e, f, g and h, and in the concavities where the panels join are embossed figures i j on each side of the dish and corresponding embossed figures k l in like position between the panels on the cover. 35

The handle D of the cover is highly ornate, its ends joining the cover on the opposite sides 40 of the transverse center of the dish and at one end has the appearance of springing from an embossed flower e, while the opposite end is environed by tendrils m, and from the end of the handle at which is the flower e spring 45 tendrils n, all of which tendrils are embossed. In the center of the handle and crossing it obliquely are graduated semispherical projections o.

The foot E of the dish is scalloped and adjacent to the body of the dish are embossed lines p. 50

What I claim is—

The design for a covered dish substantially as shown and described. 55

In testimony whereof I affix my signature in presence of two witnesses.

CHARLES A. MAY.
